UNITED STATES PATENT OFFICE.

JOSEPH O'NEIL, OF ST. LOUIS, MISSOURI.

WEATHER COVERING FOR BUILDING STRUCTURES.

Application filed January 20, 1922. Serial No. 530,646.

To all whom it may concern:

Be it known that I, JOSEPH O'NEIL, a citizen of the United States, and residing at St. Louis, Missouri, have invented the new and useful Improvement in Weather Coverings for Building Structures, of which the following is a specification.

This invention relates to building construction and more particularly to the wall construction of so-called frame buildings and the like.

In the construction of the exterior walls of frame buildings, one of three methods is usually employed. In the first of these, common boards called sheathing are nailed transversely or diagonally against the studding. Building paper is then tacked over the sheathing for insulation and so-called bevel siding or weather boarding is nailed over the building paper to the sheathing in such a manner that each piece partly overlaps the adjoining piece. It is, of course, necessary in order that the wall may withstand the action of the elements that the best quality of rot-resisting wood, such as white pine, cypress, redwood or cedar be used, and this consequently makes this method of construction a costly one.

In the second method, usually employed on cheaper buildings, tongued and grooved drop siding is nailed directly against the studding without the use of sheathing. This method requires only one operation but affords less protection against the weather. Building paper cannot be used effectively with this method as it would have to be nailed directly to the studding without any backing and the pressure of the wind through the joints in the drop siding would soon tear the paper. In both of the above methods, the nails holding the siding to the sheathing or studding are exposed to the weather and liable to rust. The joints in the bevel siding and the drop siding usually open as the wood shrinks through exposure to the weather. In order to preserve them in good condition, both the bevel siding and the drop siding must be painted at more or less frequent intervals.

In the third method of construction, sheathing is nailed to the studding as in the first method, but in place of the bevel siding, composition slate covered strips are nailed to the sheathing in overlapping relation. In the use of this method of construction, it is impossible to apply composition

strips in long lengths on account of the tendency of such a long strip to sag and tear loose from its fastenings unless supported throughout its entire length. For this reason, the composition strips are usually applied in short lengths of about 32 inches. When laid in such lengths, the joints must necessarily show on the exterior surface of the wall and as this presents an unsightly appearance, the scheme of notching the strip at intervals so as to present an appearance in imitation of shingles is usually resorted to. In this method the joints between strips may be uniformly spaced with the notches so that their presence is not evident. In this construction, the nails holding each strip may be covered by the next strip applied. This method provides a durable construction somewhat less in cost than bevel siding, but is open to the objection that the necessity for providing notches not only increases the cost, but greatly impairs the weather resisting and insulating properties of the wall.

One of the objects of this invention is to provide a method of construction which will overcome most of the difficulties mentioned above and which will combine the advantageous features of the best of the above methods.

Another object of this invention is to provide a method of construction in which a siding may be applied in long lengths by one man, thereby reducing the cost not only of the material but also of the erection.

Another object of this invention is to provide such a method of construction which will be durable and which will provide improved weather resisting and insulating properties for the wall.

Further objects will appear from the detail description taken in connection with the accompanying drawing, in which:

Figure 1 is a perspective view, partly in section, illustrating a wall construction embodying this invention;

Figure 2 is an enlarged sectional view of one of the assembly units of the construction shown in Figure 1;

Figure 3 is a view similar to Figure 1, showing another embodiment of this invention; and

Figure 4 is a sectional view of one of the assembly units of Figure 3.

Referring to the accompanying drawing, 1 designates the foundation, upon which the

frame of the structure including the plate 20 and up-rights or studding 2 may be reared in any well known manner. The assembly unit comprises a body board 3 which may 5 be of any cheap grade of lumber since it is not exposed to the weather conditions. This board is provided at its lower edge with a notch or recess 4 which is preferably tapered and rounded as shown; the upper edge of the 10 board may be formed to a receding contour as shown at 5. This receding portion may be rounded or beveled and may cover any desired extent of the surface of the board 3. An outside facing strip 6 is attached to 15 the board 3 by means of nails or other suitable fasteners 7. The strip 6 may be of any suitable variety of so-called composition siding or roofing material. This is usually a plastic base of rags and a suitable compound 20 such as asphalt to render it weather-proof and flexible, and the outside surface is usually covered with a wearing surface of finely broken slate or similar material rolled or pressed into the base. This material is very 25 durable and provides good weather-proofing and insulating qualities.

The strip 6 is attached to the board 3 near the lower edge of said board by a line of closely spaced, large headed fasteners 7 running lengthwise thereof. The strip may be 30 positioned so that an edge 8 will extend beyond the upper edge of the board 3 and a wider edge 9 will extend below the lower edge thereof. These edges provide overlaps 35 for the adjoining units as will be described later. The recess 4 provides a notch or groove between the lower edge of the board 3 and the strip 6 for a purpose which will be presently described.

40 In assembling these units in the wall structure, the first or lowermost one may be placed on the foundation so that the lower overlap or apron 9 thereof will overhang the foundation as illustrated in Figure 1. The unit is then attached to the frame 2 by 45 means of fasteners such as nails 10 spaced along the upper edge of the board 3. A second unit is then placed in the wall above the first and in such a way that the edge 8 of 50 the lower unit will engage the notch 4 of the upper unit and the apron portion 9 of the upper unit will overlap the lower unit as illustrated in Figure 1. The second unit is then fastened to the frame 2 in a manner 55 similar to that described for the first unit. It will be noted that a unit may be readily 60 slipped into place, since the tapered notch, which forms with the facing on the board, a tapering recess, can be slipped over the edge or lip 8, so that the latter will wedge into the recess and form a tight seal. Accordingly the units can be applied by one man. Subsequent units are assembled in a similar manner.

65 In this construction the receding edge 5

permits the edge 8 to be bent backward so that it will easily enter the notch 4 of the adjoining unit. The apron portion 9 of each unit will overlap a considerable extent of the next preceding unit so that at all parts 70 of the wall at least two thicknesses of the strip 6 are provided. The insertion of the edge 8 into the notch 4 provides a very effective seal between adjacent units so as to prevent leakage of the air through the joint. 75

In the embodiment shown in Figures 3 and 4 which represents a cheaper grade of construction than that described above, the body board 3 is shaped similarly to that already described. In this case, however, the strip 80 11 of composition material is narrower and has its upper edge inserted in the notch 4 and the fasteners 7 are applied at that edge, as illustrated in Figure 4. In the assembling 85 of these units, they are assembled in a manner similar to that described for the embodiment of Figure 1. In this case, however, the apron portion of each strip 11 overlaps only the body board 3 and that portion of the strip 11 at which the fasteners 7 are applied. 90

It will be evident that this invention accomplishes its objects. A method of construction is provided in which the materials may be made up into assembly units at the 95 factory and delivered in any desired lengths at the place of construction. These units may be handled in any lengths by a single operator without danger of tearing or other inconvenience. In framing around door and 100 window openings, only one cutting of the material is required instead of two as is the case when sheathing and bevel siding are used.

It will be noted that by making up these 105 assembly units in lengths corresponding to the usual siding, the units can be handled and placed in the wall in the same manner as ordinary siding and with equal facility. By this method, therefore, rapid progress is made in covering the wall or roof, since 110 a large unit of covering material is applied at one time. The application is simple and convenient since the long boards are rigid and can be handled without buckling or sagging, and they support the composition material rigidly both during application and after being placed in the wall, so that a 115 thoroughly weather-proof and permanent wall is provided.

It is obvious that various changes may be 120 made in details of construction without departing from the spirit of this invention; it is, therefore, to be understood that this invention is not to be limited to the specific details shown and described.

Having thus described the invention, what is claimed is:

1. In a weather covering for building structures, a composite unit, comprising, a body board of a length corresponding to the 130

- usual siding and of sufficient rigidity to avoid sagging when attached to the studdings, and an outside facing of composition attached to said body board, whereby said facing material is prevented from sagging. 5
2. In a weather covering for building structures, a composite unit, comprising, a body board of a length corresponding to the usual siding and of sufficient rigidity to 10 avoid sagging when attached to the studdings, and an outside facing of composition attached to said body board, whereby said facing material is prevented from sagging, said facing extending beyond said body 15 board to provide for an overlap.
3. In a weather covering for building structures, a composite assembly unit, comprising, a body board and an outside facing attached thereto and extending therebyond 20 in order to provide for overlaps at both edges of the board.
4. In a weather covering for building structures, a composite assembly unit, comprising, a body board and an outside composition facing attached thereto, constructed 25 and arranged to make an interlocking sealing joint with an adjacent similar unit.
5. In a weather covering for building structures, a composite assembly unit, comprising, a body board and an outside facing attached thereto, the upper edge of said 30 board receding, substantially as and for the purpose set forth.
6. In a weather covering for building structures, a composite assembly unit, comprising, a body board and an outside facing attached thereto, the lower edge of said board being recessed, substantially as and for the purpose set forth. 35
7. A weather covering for building structures, comprising, a series of body boards of lengths corresponding to the usual siding, and a series of corresponding composition facing strips arranged horizontally in overlapping relation on and attached to said boards, the fasteners securing said strips being spaced at frequent intervals and the fasteners securing one strip being covered by the adjoining strip. 40
8. A weather covering for building struc- 50
- tures, comprising, a series of long body boards, and a series of long composition facing strips arranged horizontally in overlapping relation on said boards, a strip being attached to one board and overlapping the board therebelow. 55
9. A weather covering for building structures, comprising, a series of long body boards, and a series of long composition fac- 60 ing strips arranged horizontally in overlapping relation on said boards, a strip being attached to one board and overlapping the board therebelow and its attached strip. 65
10. A weather covering for building struc- tures, comprising, a series of body boards, and a series of long composition facing strips arranged horizontally in overlapping relation on said boards, a strip being attached to one board and overlapping the 70 boards thereabove and therebelow.
11. A weather covering for building structures, comprising, a series of body boards, and a series of long composition facing strips arranged horizontally in overlapping 75 relation on said boards, a strip being attached to one board and overlapping the board thereabove and the strip therebelow.
12. A weather covering for building structures, comprising, a series of body boards, the upper edges of said boards receding, and a series of outside facing strips, each lying along a board and arranged to overlap the board therebelow. 80
13. A weather covering for building struc- tures, comprising, a series of body boards, the lower edges of said boards being recessed, and a series of outside facing strips, each lying along a board and arranged to lie in the recess of the board thereabove. 85
14. A weather covering for building structures, comprising, a series of body boards, the upper edges of said boards receding and the lower edges thereof being recessed, and a series of outside facing strips, each lying 90 along a board, arranged to overlap the board therebelow and lie in the recess of the board thereabove. 95

In testimony whereof I affix my signature this 13th day of January, 1922.

JOSEPH O'NEIL.
